UNITED STATES PATENT OFFICE

2,456,128

PUMP AND IMPELLER THEREFOR

Joseph S. Kessler, Kenosha, Wis., assignor to Tri-Clover Machine Co., Kenosha, Wis., a corporation of Wisconsin

Application November 15, 1946, Serial No. 709,905

5 Claims. (Cl. 103—103)

1

This invention relates to improvements in pumps and impellers therefor.

Heretofore impellers for rotary pumps of the type with which the present invention is concerned have been principally of the flat bladed type, with the blades projecting radially in opposite directions from a central axis, and with said axis lying in the plane of the blades.

It is a general object of the present invention to provide an impeller which is more suitable than the above mentioned type of impeller for certain types of uses such as the pumping of viscous liquids, or food products such as tomatoes, diced fruits, diced potatoes, soybean mash, and the like.

A more specific object of the invention is to provide an improved impeller which is formed from a flat plate, the portions of the plate on each side of its transverse center line being twisted symmetrically in opposite directions about said center line and the amount of twist being less than 90°.

A further object of the invention is to provide a pump having an impeller as above described, wherein the amount of twist on the impeller blades bears a different relationship with the width and breadth of the impeller chamber outlet.

A further object of the invention is to provide a pump construction which permits control of the pump curve characteristics by the amount of pitch provided by the twisted portions of the impeller blade to thereby adapt the pump to particular uses in such a way that the maximum efficiency is obtained.

Other objects of the invention are to provide a pump which is relatively simple and inexpensive in construction, which is strong and durable, and which is otherwise well adapted for the purpose described.

With the above and other objects in view, the invention consists of the improvements in pumps and impellers therefor, and all its parts and combinations, as set forth in the claims, and all equivalents thereof.

In the accompanying drawings, illustrating one complete embodiment of the preferred form of the invention, in which the same reference numerals designate the same parts in all of the views:

Fig. 1 is a side elevational view of a pump, parts being broken away;

Fig. 2 is a sectional view taken on the line 2—2 of Fig. 1;

Fig. 3 is a top view of the pump;

2

Fig. 4 is a plan view of the metal plate used to form an impeller before it has been twisted;

Fig. 5 is a view of the impeller looking in the direction indicated by the line 5—5 in Fig. 2; and

Fig. 6 is a view of the impeller looking in the direction indicated by the line 6—6 in Fig. 2.

Referring more particularly to the drawing, the numeral 10 designates a pump casing which in general includes a cup-shaped body portion 11 and a cover 12. The body portion 11 has a central boss 11' projecting therefrom through which a drive shaft 13 is journaled. The inner end of the drive shaft projects rotatably into the impeller chamber 14.

Projecting from the periphery of the pump body portion 11 is an outlet duct 15. The outlet duct communicates with the periphery of the impeller chamber 14 by means of an opening 16 which is the outlet opening for the impeller chamber. When the outlet passageway is circular in cross-section as at 17, and when it joins the periphery of the impeller chamber at the angle illustrated in Fig. 2, the opening 16 will be elliptical. The exact shape of the opening 16 may be varied considerably, depending upon the angle at which the outlet duct 15 intersects the periphery, and depending upon the cross-sectional shape of the passageway portion 17. In many applications it is advantageous to design the cross-section at 17 as an ellipse. When this is done the shape and dimensions of the opening 16 are varied. It is thus apparent that there may be an infinite variety of cross-sectional shapes at 17, each one producing a variation in the width *a* (Fig. 3) of the pump casing outlet, and in the breadth between the points *b* and *c*.

The impeller, designated generally by the numeral 18 is formed from a flat metal plate having the general shape shown in Fig. 4. In producing this plate the angles *d* may be varied according to the amount of twist which there is to be in the finished blade. If there is to be only a small amount of twist, then the angles *d* will be just large enough so that when the plate portions 45 are twisted about the center line *e*, the edges 19 will lie in perpendicular planes, parallel to each other, and taken along the lines 20. The amount of twist of the blade portions, of course, effects the pitch of the blades.

In designing a particular pump it is an important feature of the present invention to have the angle *f* (Fig. 5) so related to the shape of the outlet opening 16 of the pump casing that when the impeller is installed in the casing, the width 55 of the impeller between the lines 20—20 is con-

trolled so that it is substantially equal to the width *a* of the pump casing outlet (see Fig. 3), and the projected breadth *g* of the blades at their outer ends, where viewing the impeller as in Fig. 2, will be substantially equal to that dimension of the opening 16 which is at right angles to the width *c*, said dimension being the distance between the points *b* and *c*.

It is thus practical to design a pump wherein the impeller has a proper pitch for the particular product to be pumped, and wherein the outer portions of the blade have a proper dimensional relationship with respect to the breadth and width of the pump casing outlet so as to produce highly efficient results.

In assembling the pump, the impeller may be attached in any desired manner to the inner end of the impeller drive shaft 13. In the preferred embodiment of the invention the shaft is slotted as at 21 for receiving the neck portion 22 of the impeller.

The cover 12 for the pump casing may be removably secured in position by means of bolts 23 and wing nuts 24. The bolts are shown as pivotally connected to the body as at 25 so that they may be swung into and out of slots 26 in laterally projecting lugs 27 of the cover. The cover 12 has a tubular pump inlet fitting 28 projecting axially therefrom, which may be externally threaded as at 29 to facilitate the connection of an inlet line therewith.

Various changes and modifications may be made without departing from the spirit of the invention, and all of such changes are contemplated, as may come within the scope of the claims.

What I claim is:

1. A pump comprising a casing having a cylindrical impeller chamber provided with a peripheral outlet opening, an impeller rotatable in said chamber and formed from a relatively flat plate having a central neck portion and having blade portions with diverging side edges reversely twisted about the transverse center line of said neck portion, said center line forming the axis of rotation for the impeller, said blade portions being twisted to such an angle that the width of said impeller measured in a direction parallel to the axis of rotation is substantially equal to the width of said outlet opening of the casing, and so that the projected breadth of the blades near their outer ends and taken at right angles to said impeller width is substantially equal to that dimension of the outlet opening which is at right angles to said outlet opening width.

2. A pump comprising a casing having a cylindrical impeller chamber provided with a peripheral outlet opening, an impeller rotatable in said chamber and formed from a relatively flat plate having a central neck portion and having blade portions with diverging side edges reversely twisted about the transverse center line of said neck portion, said center line forming the axis of

rotation for the impeller, said blade portions being twisted to such an angle less than 90° that the width of said impeller measured in a direction parallel to the axis of rotation is substantially equal to the width of said outlet opening of the casing, and so that the projected breadth of the blades near their outer ends and taken at right angles to said impeller width is substantially equal to that dimension of the outlet opening which is at right angles to said opening width.

3. A pump comprising a casing having a cylindrical impeller chamber provided with a peripheral outlet opening, an impeller rotatable in said chamber and having blade portions reversely curved on each side of the axis of rotation of the impeller, said blade portions being curved to such an angle that the projected breadth of the blades near their outer ends and taken at right angles to the axis of rotation of the impeller is substantially equal to the length of the outlet opening in a circumferential direction.

4. A pump comprising a casing having a cylindrical impeller chamber provided with a peripheral outlet opening, an impeller rotatable in said chamber and having blade portions reversely curved on each side of the axis of rotation of the impeller, said blade portions being curved to such an angle that the width of said impeller measured in a direction parallel to the axis of rotation is substantially equal to the width of said outlet opening of the casing, and so that the projected breadth of the blades near their outer ends and taken at right angles to said impeller width is substantially equal to the dimension of the outlet opening which is at right angles to said outlet opening width.

5. A pump comprising a casing having a cylindrical impeller chamber provided with a peripheral outlet opening, an impeller rotatable in said chamber and formed from a relatively flat plate having a central neck portion and having blade portions with diverging side edges reversely twisted about the transverse center line of said neck portion, said center line forming the axis of rotation for the impeller, said blade portions being twisted to such an angle that the projected breadth of the blades near their outer ends and taken at right angles to the axis of rotation of said impeller is substantially equal to the length of the outlet opening in a circumferential direction.
